UNITED STATES PATENT OFFICE.

ALBERT ENNIS HENDERSON, OF TORONTO, ONTARIO, CANADA.

TUBE FOR PNEUMATIC TIRES.

1,255,837.

Specification of Letters Patent.

Patented Feb. 5, 1918.

Application filed December 26, 1916. Serial No. 139,008.

To all whom it may concern:

Be it known that I, ALBERT ENNIS HENDERSON, a subject of the King of Great Britain, residing at Toronto, Province of Ontario, in the Dominion of Canada, have invented new and useful Improvements in Tubes for Pneumatic Tires, of which the following is a specification.

My invention relates to improvements in inner tubes in which the tube is provided with means to prevent the pinching of the tube by the bead of the casing in that portion of the tube adjacent to the rim of the wheel. The objects of my improvements are:

First. To provide a tube which carries on or embedded in its rim side the means whereby it is protected from pinches or injury.

Second. To so arrange the protection as not to injuriously interfere with the necessary elasticity of the tube, either longitudinally or in cross section.

Third. To provide means whereby the rubber of the tube and the protecting material will be guarded against the tendency to separate under strain.

Fourth. To provide means whereby the valve base may be elastically connected with the protecting means.

In my patent for the United States, No. 1176552, dated March 21st, 1916, for which application was filed on August 11th, 1913, I have shown overlapping fabric in a tube 35 located in the tread portion having rubber interposed between the various strips, said overlapping arrangement being longitudinal.

In my patent for the United States, No. 1176553, dated March 21st, 1916, for which application was filed March 7th, 1914, I have shown both longitudinal and cross section arrangement of overlapping and elastically connected fabric in the tread portion 45 of the tube and extending around the sides thereof.

In my present application I confine the overlapping fabric to the rim side of the tube, leaving the remaining portion of the 50 body of the tube unrestrained.

I attain these objects by the mechanism

illustrated in the accompanying drawings, in which—

Figure 1, is a plan view of a portion of the completed tube with portions broken away indicating the relation of the component parts.

Fig. 2, is a sectional view of the tube showing the transverse relation of the parts shown in Fig. 1.

Fig. 3, is a sectional view of a modified form of the tube shown in Fig. 1, showing the reverse relationship of the protecting material.

Fig. 4, is a sectional view of the tube showing the transverse relation of the parts as shown in Fig. 10 in plan view.

Fig. 5, shows in cross section the reverse relation of the parts as shown in Figs. 4 and 10.

Fig. 6, is a sectional view of the tube as shown in the plan view, Fig. 12, in which the strips overlap longitudinally, with the strip 3 embedded.

Fig. 7, shows in cross section the relation of the strips as shown in plan view in Fig. 11, in which case the two inner strips are broken transversely while the outer strip is in one strip.

Fig. 8, shows a single strip embedded on the rim side of the tube unbroken longitudinally.

Fig. 9, is a sectional view of the construction shown in Fig. 12 in plan view, with this difference, that the wider inner strip is broken transversely while the outer strip is in one piece.

Fig. 10, is a plan view showing a modification of the tube which is shown in cross section in Fig. 4.

Fig. 11, is a plan view of a modification of the tube shown in cross section in Fig. 7.

Fig. 12, is a plan view shown in cross section in Fig. 6, with the strip 3 on the outside.

Similar letters refer to similar parts throughout the several views.

In Fig. 1 is shown a section of an ordinary tube, 1, having embedded on the rim side of the tube the overlapping strips of fabric 2, 2' and 3, the strips 2 and 2' being in the same plane and are broken trans-

versely at 4 and 4', the rubber of the tube 5 separating the ends of the strips. A longitudinal strip of rubber 6 separates the adjacent edges of the strips 2 and 2' from each other, while a layer of rubber 7 separates the strips 2 and 2' throughout their length from the more deeply embedded strip 3, thus providing a body of rubber between the said strips for the purpose of producing elasticity longitudinally and transversely. The strip 3 is broken transversely at 8, said breaks being disposed in such relation to the breaks in the strips 2 that the ends will overlap longitudinally. The base 9 provided with a slot 10 to permit the insertion of the valve stem from without the tube is so arranged relative to the protecting strips 2 and 3 as to provide an overlapping elastic connection between the base and the protecting strips of the tube.

I do not confine myself to the construction of base as shown in Fig. 1, as any form of base may be used, provided there is the overlapping elastic connection between the base and the protecting strips. The strips 2, 2' and 3 may be shown in cross section embedded as in Figs. 1 and 2, in which case the sections of the strips 2 and 2' are embedded nearer the surface of the tube than the sections of the strip 3, or as in Fig. 3, in which the sections of the strips 2 and 2' may be more deeply embedded than the sections of the strip 3.

In Figs. 4 and 10 the sections of the strips 2 and 2' are adjacent to the surface of the tube while the strip 3 is embedded and separated from the strips 2 and 2' by a body of rubber throughout their entire length.

In Fig. 5 the sections of the fabric strip 3 are shown adjacent to the surface of the tube while the strips 2 and 2' are embedded and separated from the strip 3 by rubber.

In Fig. 6 the strips 3 and 11 are broken transversely so that the ends overlap, thus providing for longitudinal expansion of the rim side of the tube when necessary.

In Figs. 7 and 11 the strip 12 is shown unbroken transversely, while the strips 2 and 2' are broken transversely at 13 and separated by the rubber strip 14 provide for transverse expansion of the tube and longitudinal expansion in that portion of the tube which extends transversely beyond the limits in cross section of the strip 12, designated at 16.

In Fig. 9 the outer strip 12 is one continuous piece, as in Figs. 7 and 11, while the strip 11 is broken transversely as at 17, the ends of the fabric being separated by the rubber 18, thus providing longitudinal expansion only outside the limits laterally of the strip 12.

In Figs. 1, 10, 11 and 12 the wall of the

tube has been broken away at 19, 20, 21 and 22 respectively, showing that not only are 65 all the strips separated from each other by rubber but in no part of the tube are the strips in frictional contact with each other; thus the danger of separation of the fabric from the rubber of the tube has, to a great 70 extent, been eliminated.

In Fig. 8 a single strip 15 has been used which may be cut on the bias, thereby reducing the tendency to separate from the rubber of the tube under strain, although it is possible to use the strip 15 either embedded or adjacent to the rim side surface of the tube and thereby providing a protection.

It will be seen from the drawings and specifications thus far that I have provided 80 an elastic protection for the rim side of the tube which will replace the ordinary flap which is used to prevent the tube from being pinched by the show of the outer casing and by the application of the overlapping principle have overcome the difficulties which are incident to any attempt to provide a tube with protecting fabric where this principle is not applied.

I do not limit myself to the construction 90 shown in the drawings as to the connection of the protecting fabric with the valve base, but may vary the construction as may be expedient, and would also point out that wherever the fabric overlaps, as at point 95 23, it would be possible to insert a valve stem on the rim side of the tube, having the fabric adjacent to the reduced shoulder of the valve stem, thereby permitting the same to be engaged by the compressing washers of the 100 valve stem.

The specific construction of the valve base disclosed herein is made the subject matter of co-pending application filed by me January 27, 1917, Serial No. 144,911.

I do not confine myself to the construction shown in the drawings and described in the specifications as certain modifications in the application of the principles of my invention may be used without departing from the 110 spirit of my invention.

I claim:

1. A tube for pneumatic tires having its rim side portion provided with an embedded protection and valve base, the same comprising a series of unconnected, longitudinally overlapping inelastic fabric strips.

2. A tube for pneumatic tires having its rim side portion protected by a series of unconnected terminally overlapping fabric strips embedded therein adjacent to the surface of the tube, a valve base overlappingly connected with the said protecting strips.

3. In combination with a tube for pneumatic tires, having its rim side portion protected by a series of unconnected fabric

strips embedded therein adjacent to the surface of the tube and spaced apart by intermediate rubber a valve base adapted to receive from without the button of the valve 5 stem, said valve base being overlappingly connected with the said protecting series.

In testimony whereof I have hereunto

affixed my signature in the presence of two witnesses.

ALBERT ENNIS HENDERSON.
